KNITTING METHOD AND MACHINE
THEREFORLester Mishcon, Brooklyn, N. Y., assignor to
Supreme Knitting Machine Co., Brooklyn,
N. Y.

Application May 18, 1937, Serial No. 143,276

7 Claims. (Cl. 66—9)

This invention relates to a method and machine for knitting a fleece fabric, and particularly for manufacturing a cloth containing on one side thereof a fleece or laid-in yarn, the opposite side having a clean solid back.

In the manufacture of various types of fabrics, particularly cotton-back overcoating, the method generally employed therefor has heretofore entailed the employment of a machine with spring 10 beard needles. Attempts have also been made to fabricate a cloth of this nature on circular open top latch needle machines by laying in floats of one or more yarns within the main body of the material. Particularly where this was done 15 on a latch needle machine, the laid in yarn was generally partially visible on the reverse side,—some of the said lay-in portions actually protruding therefrom. It is one of the objects of this invention to enable a backing cloth or fleece fabric to be knitted on a circular open top latch 20 needle machine in such a way as to provide the outside face of the tubular cloth with a clean solid back, without any of the floated yarns being visible.

It is within the contemplation of this invention to accomplish the aforesaid purpose without the necessity of materially altering the structure of the conventional circular open top knitting machines. And I accomplish this objective by producing, during the knitting operation, lay-in on 30 an upper level wholly independent and separate from the knitting operations performed on the lower level.

Other objects, features and advantages will 35 appear from the drawing and the description hereinafter given.

Referring to the drawing,

Figure 1 is a semi-diagrammatic development 40 of a portion of the knitting machine, preferably of the open top circular type, constituting my invention.

Figure 2 is a diagrammatic representation of a portion of the fabric made by the method of Figure 1, and

Figure 3 is a fragmentary semi-diagrammatic section of Figure 2 taken along line 3—3.

In the drawing, the double throat sinker 5 is operated by a conventional sinker actuating 50 cam in a manner to be hereinafter described. Said sinker contains the throats 6 and 7, containing the ledges 8 and 9 respectively. And within the contemplation of this arrangement, there are two sinker lines or levels 10 and 11, the former being substantially at the level of ledge 8 and rep-

resenting the level at which the inlaid floats are held during the operation of the machine, and the latter substantially at the level of ledge 9 and representing the level of the completed fabric.

In the particular form of the apparatus shown 5 in the drawing, a conventional cam ring is provided rotatable about the cylinder which contains a plurality of vertically movable needles,—although this invention is equally applicable to a structure where the needle cylinder is rotatable 10 and the said cam ring stationary. Inasmuch as the structure of the cam ring and needle cylinder is well understood in the art, it is not illustrated in the drawing, being of the conventional construction as generally employed in circular open 15 top latch needle machines. Suitably mounted upon the cam ring are a plurality of approach cams and needle elevating means, which may be pattern wheels or cams, as well as coacting stitch cams.

Referring specifically to the drawing, the approach cams 12, 13, 14 and 31 are movable in the direction of the arrow about the needle cylinder. Cooperatively positioned with respect to the said 20 cams are the selector wheels 15, 16, 17 and 32 respectively, and the stitch cams 18, 19, 20 and 33 respectively. In the construction shown, the selector wheels 16 and 17, being of the jack type, have all their slots filled, so that all the needles 25 coming into engagement with said two wheels will be elevated thereby. It is therefore obvious that for the particular arrangement shown in Figure 30 1, instead of employing design wheels, cams may be used.

In the operation of this device, when groups 35 of three feeds are employed about the cylinder, the needles engaging the selector wheel 15 are selectively raised in accordance with the arrangement of jacks within the slots on the wheel. It 40 will thus appear that the needles 21 pass directly through the unfilled slots, whereas the needles 22 which encounter jacks are elevated. At this first feed, the needles 22 are elevated by the wheel 15 to a position preferably below the latch clearing 45 level with respect to the lower sinker level 11, the needles in this position being at a sufficient height to enable them to engage within the hook thereof the yarn 23 supplied by a guide 24,—said 50 yarn 23 being the lay-in yarn adapted to make a float within the body of the material as will hereinafter appear. It is to be understood, however, that it is possible, within the contemplation of this invention, to elevate the needles 22 at the first feed to a position above the latch clearing 55

level with respect to the sinker level 11, to obtain substantially the same results.

As the elevated needles 22 engage the stitch cam 18, these needles will be drawn down to a position where the tops thereof are slightly below the sinker level 10, but not sufficiently to cast off the cloth switches from the previous cycle of knitting. It should be noted that while the aforesaid operation is being performed, the cloth or 10 stitches and floats from the previous cycle of knitting remain at the lower level 11, which is obviously due to the fact that the selector wheel 15 raised the needles to a height below the latch clearing level with respect to the sinker line 11, as shown in the specific arrangement illustrated in Figure 1.

It will further be observed that the new inlaid yarn 23, particularly at the position in the region designated by the reference letter R after being 20 brought to that position by the stitch cam 18, is actually suspended substantially at the upper level 10, not having any connection whatsoever with the lower portion of the fabric at level 11, as will more clearly appear from the description 25 hereinafter given.

As the approach cam 13 and wheel 16 progress in the direction of the arrow, all needles elevated by the wheel will be raised to a latch-clearing position with respect to the upper level 30 10, the tops of the needles being brought substantially to the level 25. This of course is accomplished by positioning the selector wheel 16 at such a level to produce this result, being at a higher level than that at which the wheel 15 is 35 positioned,—the approach cam 13 being also necessarily at a higher level than the cam 12 so that it may properly coat with the wheel 16. At the said level 25, the hooks of the needles 21 and 22 will receive the intermediate body yarn 26 supplied by the guide 27. Thereafter, these 40 needles are drawn down by the stitch cam 19 to a level slightly below the sinker level 10, casting off only the lay-in yarn 23,—thereby interlacing the inlaid floats from the previous feed while 45 still retaining all the previously completed stitches at substantially the level 11.

At this point, the needles leaving the cam 19 have the inlaid yarn 23 at the rear of and slightly above the needles and the said intermediate yarn 50 26 within the hooks of the needles. It will be understood that the original cloth comprising the previously knitted fabric up to this point has merely been suspended on the needles that 55 operatively pass over cams 12 and 13, inasmuch as the needles were never drawn down lower than the sinker level 11 by the cams 18 and 19. The said previously knitted stitches remain hanging on closed latches of the needles while the float of inlay yarn is being tied in by the stitch cam 19, and remain that way with the floats of inlay yarn 60 23 at the rear of the needles held by the yarn 26 which, as aforesaid, is still in the hooks of the needles.

As the approach cam 14 continues to progress 65 in the direction of the arrow, the selector wheel 17 elevates all needles operatively engaged thereby to a height where the latches of these needles to not quite clear the upper sinker level 10, being slightly therebelow. The hooks of the needles are hence brought to the level 29, which is below the level 25 to which the needles were brought by the selector wheel 16; and at this point, the needles engage within their hooks the main yarn 28 supplied by the guide 30. Thereafter these needles 70 75 are drawn down by the stitch cam 20 to a cast-off

position below the lower sinker level 11, thereby knitting stitches of the main yarn 28 and the intermediate yarn 26, the tied-in floats remaining incorporated in the fabric as an inlaid yarn. It is of course obvious that the positioning of the 5 needles at the last mentioned feed is effectuated by positioning the selector wheel 17 at a level intermediate the positions of the selector wheels 15 and 16, the approach cam 14 and stitch cam 20 occupying corresponding coating positions. It 10 should be noted that at this stage the hooks of the needles contain two threads of yarn 26 and 28.

This cycle repeats itself for as many groups of feeds as there are on the machine. If, however, it should be required to have an arrangement 15 whereby two different sets of needles take a floated yarn, an additional feed is added at the beginning of each group of feeds, containing an arrangement such as the approach cam 31, the selector wheel 32, the stitch cam 33 and the inlay 20 yarn 34 supplied by the guide 35. The elements of this last mentioned feed are precisely in the same position as those at the first feed containing the approach cam 12, the selector wheel 5, stitch cam 18 and lay-in yarn 23. Thus with such 25 an arrangement, there are four feeds to a unit all within the contemplation of this invention.

In order to operatively permit the aforesaid knitting and lay-in operations to be performed, the sinker 5 is operated by an actuating cam of 30 the conventional structure, this cam being so arranged as to move the sinkers 5 into the dotted line position shown in Figure 1, as will more clearly appear from the description hereinafter given.

At the first feed above the approach cam 12, the sinkers 5 are drawn back sufficiently far to enable the nose 36 of the sinker to be cleared by the yarn 23 thereby enabling it to operatively take the float formed from said yarn 23 at the 40 sinker level 10.

At the feed above the approach cam 13, the position of the sinker cam is the same as for the first position above described, allowing all needles to take the yarn 26 for tying in all the floats at 45 said needles, but still permitting said floats to remain suspended at the level 10 after the stitch cam 19 operatively passes on to the right.

At the feed above the approach cam 14, the sinker actuating cam draws the sinkers 5 still 50 further back, as shown by dotted lines, so as to enable the nose 37 to be cleared. This permits interlaced floats from the upper level 10 to be dropped off to lower level 11, allowing the yarn 28 to be operatively fed into the hooks of the 55 needles and operatively drawn down by the stitch cam 20. At this point, as above described, it is apparent that all the yarn comprising the original fabric from the previous cycle of knitting will 60 be cast off, the yarns 26 and 28 still being in the 65 hooks to be knitted in at another knitting group.

It should further be noted that all needles substantially extending across the distance "A" have the wales of the previously finished fabric hanging upon the needles at level 11, and a float on 65 the selected and previously elevated needles suspended at the level 10. All the needles extending substantially across the distance "B" have the wales of the previously finished fabric suspended upon the needles at the level 11, the inlaid yarn 70 75 23 being in back of the needles and the intermediate yarn 26 being in front of the needles and interlaced with the inlay yarn 23. All needles thereafter have already interknitted all previous floats and finished fabrics.

Employing the method and machine above described, the fabric such as illustrated in Figures 2 and 3 can be obtained, the lay-in yarn being designated by the reference numeral 23a, and the intermediate and main yarns being represented by the reference numerals 26a and 28a respectively. It is apparent from an inspection of Figure 3 that one side of the cloth is provided with a continuous arrangement of spaced wales composed of the main yarn 28a, thereby providing one substantially solid surface without any inlaid yarns extending therethrough,—said surface being readily adaptable as the backing for a fleece fabric.

It thus appears that the method and apparatus above described, which relates to a single phase of knitting in accordance with this invention, enables the manufacturer of a fleece or laid-in yarn fabric on the inside face of the tubular cloth being fabricated, while the outside face of the cloth has a clean solid back without any inlay or floated yarns visible. This is essentially effectuated by the hereinbefore described arrangement whereby the lay-in is floated and interlaced on the upper level 10, being wholly independent of the operations performed at the lower level 11,—this being a novel arrangement for circular open top latch needle machines.

It is of course understood that other additional forms and modifications of the apparatus and adaptations of the method constituting this invention can be employed beyond and in addition to those hereinbefore described, all within the scope of the appended claims.

35 What I claim is:

1. In a circular open-top latch needle knitting machine, double-throated sinker means providing an upper and a lower sinker level, a plurality of spaced yarn feeds including three successive feeds for supplying an inlay yarn, an intermediate body yarn and a main yarn, respectively, needle elevating and depressing means at each of said feeds, the said needle elevating means being adapted to raise coacting needles at said intermediate feed to above latch-clearing position with respect to the upper sinker level, and at the main yarn and inlay yarn feeds to below the latch-clearing position with respect to the upper sinker level, the said needle depressing means being adapted to lower the needles at the inlay and intermediate yarn feeds to substantially the upper sinker level and short of cast-off position, and at the main yarn feed to below the lower sinker level and below the cast-off position with respect thereto.

2. In a circular open-top latch needle knitting machine, a plurality of circumferentially disposed double-throated radially movable sinkers providing an upper and a lower sinker level, a plurality of spaced yarn feeds including three successive feeds for supplying an inlay yarn, an intermediate body yarn and a main yarn, respectively, needle elevating and depressing means for actuating certain predetermined needles to successively draw loops of yarn from each of said feeds, the said needle elevating means being adapted to raise coacting needles at said intermediate feed to above latch-clearing positions with respect to the upper sinker level, and at the main yarn and inlay yarn feeds to below the latch-clearing position with respect to the upper sinker level, the said needle depressing means being adapted to lower the needles at the inlay and intermediate yarn feeds to substantially the upper sinker level and short of cast-off position, and at the main

yarn feed to below the lower sinker level and below the cast-off position with respect thereto, said sinkers being adapted to receive at said upper sinker level the yarn at said inlay and intermediate feeds, and at said lower sinker level at the 5 main yarn feed.

3. In a circular open-top latch needle knitting machine having an upper and lower sinker level, three successive feeds for supplying an inlay yarn, an intermediate body yarn and a main yarn respectively, means for actuating certain predetermined needles to successively draw loops of the inlay yarn down to substantially said upper level, clear the latches of said inlay yarn and draw loops of said intermediate yarn to substantially 10 said upper level and short of the casting off position for interlacing a float of said inlay yarn without knitting, and means for subsequently actuating said needles to draw loops of the main 15 yarn and the intermediate body yarn to a casting off position below said lower sinker level, thereby operatively knitting and tying in the 20 previously formed stitches and float.

4. In a circular open-top latch needle knitting machine having an upper and lower sinker level, 25 a plurality of spaced feeds including three successive feeds for supplying an inlay yarn, an intermediate body yarn and a main yarn, respectively, needle elevating means at each of said feeds including a selector wheel at the inlay yarn 30 feed for selectively elevating coacting needles to a level for operatively taking the inlay yarn, means for lowering the said selected needles to a point substantially at said upper level and short of the casting off level to form a float of 35 inlaid yarn substantially at said upper level, means at the intermediate yarn feed for elevating coacting needles to a latch-clearing position relative to said upper level and for operatively taking said intermediate yarn, means for lowering said needles to a point substantially at said upper level and short of the casting-off level for interlacing said inlaid float with said intermediate 40 yarn at said upper level, means at said main yarn feed for raising coacting needles to a level 45 for operatively taking the main yarn and short of clearing the latch of said intermediate yarn at said upper level, and means for lowering the needles to a point below the said lower sinker 50 level for casting off and operatively knitting and tying in the said previously formed stitches and float.

5. In a method of knitting on a circular open-top latch needle machine, the steps of successively elevating selected needles to a position for taking a yarn to be inlaid, operatively supplying said yarn to said needles, lowering said needles to a predetermined upper sinker level short of the casting-off level of previously formed stitches, thereby forming a float of inlaid yarn, raising 60 said needles and the unelevated needles to a latch-clearing level, supplying an intermediate yarn to said needles, lowering said needles to said upper level short of the casting-off level of said previously formed stitches and casting off and interlacing said inlaid float, elevating said needles to a level for taking a main yarn and below the latch-clearing level for the said previously taken intermediate yarn, supplying a main 65 yarn to said needles, and drawing down all the needles to below a predetermined lower sinker level for casting off and operatively knitting and tying in the said previously formed stitches and float.

6. In a circular open-top latch needle knitting 75

5 machine, double throated sinker means providing an upper and a lower sinker level, a plurality of spaced yarn feeds including three successive feeds for supplying an inlay yarn, an intermediate body yarn and a main yarn, respectively, to the needles when the needles are at different levels; said inlay yarn feed being adapted to supply its yarn to needles that are at the lowest of said levels, said intermediate yarn feed being adapted to supply its yarn to needles that are at the highest of said levels; needle elevating and depressing means for actuating certain predetermined needles to successively draw loops of yarn from each of said feeds, respectively, said latter means being adapted to raise and lower coacting needles to predetermined points with respect to said upper and lower sinker levels.

7. In a circular open-top latch needle knitting machine, double throated sinker means providing an upper and a lower sinker level, a plurality of spaced yarn feeds including three successive feeds for supplying an inlay yarn, an intermediate body yarn and a main yarn, respectively, to

the needles when the needles are at different levels; said inlay yarn feed being adapted to supply its yarn to needles that are at the lowest of said levels, said intermediate yarn feed being adapted to supply its yarn to needles that are at the highest of said levels; needle elevating and depressing means for actuating certain predetermined needles to successively draw loops of yarn from each of said feeds, respectively, the said needle elevating means being adapted to raise coacting needles at said intermediate feed to above latch-clearing position with respect to the upper sinker level, and at the main and inlay yarn feeds to below the latch-clearing position with respect to the upper sinker level, the 10 said needle depressing means being adapted to lower the needles at the inlay and intermediate yarn feeds to substantially the upper sinker level and short of cast-off position, and at the main 15 yarn feed to below the lower sinker level and 20 below the cast-off position with respect thereto.

LESTER MISHCON.
